UNITED STATES PATENT OFFICE.

WILLIAM H. LARAWAY AND LOUIS V. LILLIBRIDGE, OF GRAND RAPIDS, MICHIGAN.

COIN-CONTROLLED VENDING MACHINE.

Application filed November 27, 1922, Serial No. 603,496. Renewed December 26, 1924.

To all whom it may concern:

Be it known that we, WILLIAM H. LARAWAY and LOUIS V. LILLIBRIDGE, citizens of the United States, residing at Grand Rapids, in the county of Kent and State of Michigan, have invented certain new and useful Improvements in Coin-Controlled Vending Machines, of which the following is a specification.

Our invention relates to improvements in vending machines, and its objects are: first, to provide a means whereby the coin operating mechanism will be made to act positively and without danger of error; second, to provide a means whereby the danger of repeating the operation of the machine with a single action of the coin will be eliminated, and, third, to provide a means whereby the coin actuating mechanism may be properly 20 and readily adjusted in case of over wear or displacement.

We attain these objects by the mechanism and arrangement of parts shown in the accompanying drawing, in which Fig. 1 is a sectional elevation of the end of the case on the line 1—1 of Fig. 2. Fig. 2 is a front elevation of the case. Fig. 3 is a top plan of the case. Fig. 4 is a transverse section of the machine practically upon the line 30 4—4 of Fig. 1. Fig. 5 is a sectional plan of the same upon the line 5—5 of Fig. 1. Fig. 6 is an end perspective of the coin conducting block, and Fig. 7 is a plan of the sliding box that transfers the vials from the machine into position to be readily taken by the operator.

Similar reference characters indicate similar parts throughout the several views.

In the construction of this machine we make a case consisting of the back 1, the partitions 2 and 3 which form storage slots for the bottles 19, a door 4, and a base consisting of the ledge 6, a supporting beam for the bottles, as at 5, a table 7 having slots 8 therethrough for the passage of coin, a ledge 9 for preventing the outcoming bottles from rolling off of the table, and a case door 10. These features are, in a sense, common in vending machines, as is, also, the guide plate 11, the actuating bar 12 hinged to a base 14 as at 13.

The mechanism for transferring the bottles of perfume from their receptacle to the table 7 consists of a receiving slide or open box 18 that lies, normally, upon the beam, or bed 5. This box or receptacle has a back-

wardly extending arm 17 terminating in a head *h*. This arm passes through the lower end of the partition 2, as indicated in Fig. 1, and an actuating spring 17' is placed 60 thereon which is designed, first, to draw the receiving box backwardly into normal position upon the supporting beam 5, and, second, to force the actuating levers 16—16' back into normal position after having been 65 made to force the receptacles 18 into position to discharge a bottle upon the table 7. The actuating levers are pivotally mounted upon the machine back, as at *k*, and are composed of the slotted end 16, for 70 the reception of the actuating coin *m* which is passed through the slot 8 in the table 7, and thence rolls through the slots *c* in the frame 11—11' into the slots *d* in the actuating levers 16 and are held upon the ledge 75 *i* on the base 15. The base 15 is provided with openings *a* for the passage of the sides of the staples 20. The staples 20 are secured into one edge of the bar 12 and extend outward therefrom into position 80 to engage the coin at *m'*, when the bar 12 is forced to swing downwardly by means of the lever 22 and knob 21, as indicated by the dotted lines in Fig. 2. When the coin is in the position indicated at *m'* 85 the lever 16 stands in its normal position, but when forced down upon the ledge *j*, by the downward movement of the staple 20 the lever is moved slightly from its normal position, and when the coin is forced downward into the position indicated at *m''* 90 the lever is swung upon its pivot bearing sufficiently to carry a bottle 19 off of the ledge or beam 5 and allow it to drop upon the table 7 and roll to the ledge 9 ready to 95 be taken from the machine.

The bases 14 and 15 are slotted, as at *g*, so the screws may be loosened and the bases adjusted backwardly or forwardly, as desired.

At *a* we have shown the front line of the base 15 and *b* represents the back line of the base 14. At *d* we have shown the slot in the levers 16, and *e* is the dotted outline of the bottle carrier 18 showing its position when discharging a bottle, *f* indicates the hinges that carry the door 10 for opening and closing the lower part of the case.

The upper part of the door 4' may be made of a translucent material, or may be utilized for advertising purposes, as desired, 110 or the entire door may be covered with

transparent glass, if preferred, so as to exhibit the several columns of bottles 19 as indicated at 4" in Fig. 2.

Having thus fully described our invention, what we claim as new in the art, is:—

1. In combination with a vending machine for selling bottles, and the coin actuated levers therein, a coin actuating bar pivotally supported, at one edge, upon a base, said base made adjustable backwardly and forwardly, staples secured into, and projecting from the free edge of the bar, a second adjustable base having slots cut downwardly from its upper edge for the free passage of the sides of the staples in their downward movement for actuating the coin.

2. In combination with a coin operated vending machine and its actuating levers and coin slots, a coin actuating bar pivotally mounted upon an adjustable base, wire staples secured into, and projecting backwardly from the free edge of the bar, a guide base adjustably secured under said staples, said base having slots formed downwardly from its upper edge for the free passage of the side arms of the staples, said base having ledges upon its back surface for checking the movements of the coin when operating the machine.

Signed at Grand Rapids, Michigan, November 21, 1922.

WILLIAM H. LARAWAY.
LOUIS V. LILLIBRIDGE.
